UNITED STATES PATENT OFFICE.

JOHN H. FORSTER, OF NEW ULM, MINNESOTA.

DESIGN FOR A SNAP-HOOK MEMBER.

SPECIFICATION forming part of Design No. 30,897, dated May 30, 1899.

Application filed June 11, 1898. Serial No. 683,232. Term of patent 7 years.

To all whom it may concern:

Be it known that I, JOHN H. FORSTER, residing at New Ulm, in the county of Brown and State of Minnesota, have invented and 5 produced a new and useful Design for a Snap-Hook Member, of which the following is a specification.

This invention is a new and useful design for a snap-hook member, the leading feature 10 being the peculiar shape hereinafter fully described in detail.

The figure in the drawing represents my invention in perspective.

As seen in the drawing, A represents the 15 body portion, shaped at one end and centrally

to form curved wings B. The body portion at the juncture of these wings is flat along its entire length, as seen at C. To the rear end of the body portion is formed a rectangular loop D, surrounding the rear end of 20 which is a sleeve E.

Having thus fully described my invention, what I claim, and desire to secure by Letters Patent, is—

The design for a snap-hook member substantially as described.

JOHN H. FORSTER.
